UNITED STATES PATENT OFFICE.

IRWIN CHASE, OF BAYONNE, NEW JERSEY, ASSIGNOR TO THE ELCO COMPANY, OF BAYONNE, NEW JERSEY, A CORPORATION OF NEW JERSEY.

DESIGN FOR A PLEASURE-CRUISER.

48,220.

Specification for Design.

Patented Nov. 30, 1915.

Application filed February 3, 1915. Serial No. 5,979. Term of patent 7 years.

To all whom it may concern:

Be it known that I, IRWIN CHASE, a citizen of the United States, residing at Bayonne, county of Hudson, and State of New Jersey, have invented a new, original, and ornamental Design for Pleasure-Cruisers, of which the following is a specification, reference being had to the accompanying drawings, forming a part thereof.

Figure 1 is a side elevation of a pleasure cruiser built in accordance with my new design. Fig. 2 is a plan view of the same.

Copies of this patent may be obtained for five cents each, by addressing the "Commissioner of Patents, Washington, D. C."

I claim:

The ornamental design for a pleasure cruiser, as shown.

In testimony whereof, I, affix my signature, in presence of two witnesses.

IRWIN CHASE.
